UNITED STATES PATENT OFFICE.

GUNNAR MADVIG, OF OAKLAND, CALIFORNIA.

DESIGN FOR A CENTER ORNAMENT FOR DRAPERY POLES OR RODS.

Application filed April 23, 1928. Serial No. 26,430. Term of patent 3½ years.

To all whom it may concern:

Be it known that I, GUNNAR MADVIG, a subject of the King of Denmark, and a resident of the city of Oakland, county of Alameda, State of California, have invented a new, original, and ornamental Design for a Center Ornament for Drapery Poles or Rods, of which the following is a specification, reference being had to the accompanying drawing, forming part thereof.

The drawing is a side view of the center ornament illustrating my new design.

I claim:

The ornamental design for a center ornament for drapery poles or rods substantially as shown.

GUNNAR MADVIG.
